UNITED STATES PATENT OFFICE.

TIMOTHY G. DALY, OF REVERE, MASSACHUSETTS, ASSIGNOR TO GEORGE E. SMITH, OF BOSTON, MASSACHUSETTS.

DESIGN FOR AN ADVERTISING-CASE.

SPECIFICATION forming part of Design No. 33,175, dated September 4, 1900.

Application filed July 25, 1900. Serial No. 24,822. Term of patent 14 years.

To all whom it may concern:

Be it known that I, TIMOTHY G. DALY, of Revere, in the county of Suffolk and State of Massachusetts, have invented and produced 5 a new and original Design for an Advertising-Case, of which the following is a specification.

This invention relates to a new and useful design for an advertising-case; and it consists in the novel features of shape and configuration hereinafter fully described and particularly claimed, and clearly illustrated in the drawings.

Reference is to be had to the accompanying drawing, forming a part of this application, 10 in which like characters indicate like parts wherever they occur.

The figure represents a partial perspective view showing my design.

The essential feature of my design consists 15 in a base portion provided upon its face with a lattice-work ornamentation having a conventional ornamental border, said base being formed with a vertical extension having a

plane face surrounded by a conventional ornamental border. From each side of the base 25 portion is a cylindrical-shaped member.

1 represents the base portion.

2 represents the lattice-work ornamentation.

3 represents the conventional ornamental 30 border.

4 represents the vertical extension of the base portion.

5 represents the plane face.

6 represents the conventional ornamental 35 border, and 7 represents the cylindrical-shaped member.

I claim—

The design for an advertising-case, as shown and described.

In testimony whereof I have affixed my 40 signature in presence of two witnesses.

TIMOTHY G. DALY.
